DISPLAY POSTER

Richard E. Paige, New York, N. Y.

Application December 13, 1941; Serial No. 422,862

4 Claims. (Cl. 40—152.1)

This invention relates to new and useful improvements in display devices and more particularly it pertains to a display poster.

It is the primary object of the invention to provide a poster which may be cheaply manufactured as compared in price with such devices as generally constructed.

It is a further object of the invention to provide a poster which comprises a minimum number of parts.

It is a still further object of the invention to provide a device of the aforementioned character which may be readily erected from knock-down form to display position and which may as readily be disassembled from display position.

It is a further object of the invention to provide a novel construction by means of which the poster or display element and its support are separate elements which may be packed together in bulk with the supporting means in a flat folded position.

It is a still further object of the invention to provide a novel construction whereby the poster when set up in display position will present a neat, smooth, unwrinkled appearance.

With the above and other objects in view, reference will now be had to the accompanying drawing in which,

Figure 1 is a rear perspective view illustrating a device constructed in accordance with the present invention in its set-up or display position;.

Figure 2 is a view in side elevation thereof; and

Figure 3 is a vertical sectional view on an enlarged scale partly broken away taken substantially on the line 3—3 of Figure 1.

Referring to the drawing, by reference characters, the reference character A designates the poster element; and B designates the support therefor.

The poster element is of a non-rigid nature, being preferably formed of paper as distinguished from the paperboards, cardboards and the like generally employed.

In the present embodiment of the invention, the poster element is shown as of greater height than width, and extending across its top edge and its bottom edge, there is a rigid reinforcing or strut member C.

The strut members C are preferably formed from cardboard or similar material relatively more rigid in character than the material from which the poster A is formed, and as best illustrated in Figure 2 of the drawing, they are of channel shaped cross section. Inasmuch as both

of the strut members C preferably are of the same construction, the description of one will suffice.

A strut member C comprises two side walls 10 connected by an intermediate wall 12 which construction forms a channel. The poster element A is secured to each strut member C upon the outer face of the wall 12 only thereof, and not to the outer face of either of the side walls 10; the points of attachment of the poster element with the reinforcing members being designated 14 in the drawing.

By this construction, the poster element A, when placed under tension, will stretch smoothly over the outer faces of the walls 10 of the reinforcing members across which the poster extends and will present a neat and unwrinkled appearance upon the front or display face of the poster element.

Means is provided for supporting the poster element in upright display position, which means also serves to maintain the poster in its extended display position, preferably, although not necessarily, under tension, and this means will now be described.

The support comprises an easel-like element B. This easel-like element comprises two wings 18 and 20, which are connected by an intermediate element 22.

The support is formed from a single blank of material which is scored along two lines 24 and 26, see Figures 2 and 3 respectively, to provide the two wing sections 18 and 20 and the intermediate connecting element 22 thereof. The score lines 24 and 26 form the means upon which the wing members 18 and 20 may hinge into substantially parallel planes substantially at right angles to the connecting element 22 when it is desired to set the support up for use, in which position they may be retained by interlocking tongues 30 and 32, which are slotted as at 34 for interengagement with each other as illustrated in Figure 3 of the drawing. Preferably the rear edges of the wing sections 18 and 20 taper from their lower supporting edges 36 in the direction of their upper end edges 38. This construction provides a sufficient support for the easel-like support and permits of effective concealment of the upper end of the support behind the poster when the same is set up.

Each of the wing members 18 and 20 is provided upon its upper end with a slot 40 and upon its lower end with a slot 42, these slots 40 and 42 are spaced from the forward edges of their respective wing members by a distance substantially equal to that between the inner faces of the

side walls 10 of the channel shaped reinforcing members C, and each is adapted to receive one of the side walls 10 of the reinforcing members to provide a means for attaching the poster element to the support.

The construction just described provides portions 44 at the forward edges of the wing members 18 and 20 which lie between the slots 10 and the rear face of the connecting element 22 of the support, the width of which is substantially equal to the space between the side walls 10 of the strut members C.

The manner in which the poster is shipped, and upon reaching its destination, is set up for display will now be described.

A number of poster elements each of which may be rolled if desired, together with a corresponding number of supporting elements, preferably in flat form, are placed in a suitable container for shipment.

When it is desired to set up the posters, the supporting element is first erected by folding or hinging the wing members 18 and 20 about their respective score lines 24 and 26 into substantially parallel planes, after which the tongues 30 and 32 are interlocked with each other to maintain the support in its erected form.

After the support has been set up, the poster element is attached thereto by inserting the portions 44 at the opposite ends of the support between the side walls 10 of their respective strut members C of the poster. In so doing, one of the side walls 10 of each of the strut members C will enter its respective slot 40 or 42 in the wing members 18 and 20, in which they will be frictionally held to provide means of attachment of the poster element A to the support B.

It will be understood that there is a definite relation between the vertical dimension of the poster element A and that of the support B, and this relation is such that when the strut members C are engaged with their respective slots in the wing members of the support, the non-rigid poster element will be extended under sufficient tension to cause it to present, in spite of its non-rigid character, a smooth and unwrinkled front display surface.

Furthermore, by reason of the fact that the poster element is not secured to the front faces of the side walls 10 of the reinforcing members C, the same will lie flat against these side walls of the reinforcing members also presenting a smooth and unwrinkled surface at these points.

From the foregoing, it will be apparent that the present invention provides a new and improved construction in displays of the poster type in which the poster element may be formed from paper, a relatively cheaper substitute for card board, thus materially reducing the cost of manufacture of articles of this character.

It will also be apparent that a highly desirable result is obtained by the use of a minimum number of separate parts, there being but two, namely, the poster and the support therefor.

This last result is obtained by reason of the fact that the support performs two functions, namely, it provides the only supporting means for the poster element, and at the same time provides means for maintaining it in its extended display position under tension.

I am aware that non-rigid posters and rigid supporting elements therefor have been heretofore employed in the art, but in none of these devices with which I am familiar is there a single element which provides the double function of

stretching or maintaining a poster of a non-rigid character in extended display position under tension, and at the same time provides the sole supporting means therefor.

5 It is to be understood that the invention is not to be limited to the specific construction herein illustrated and that the term single means employed in certain of the claims is not to be construed as meaning a single supporting element since obviously, in the case of a poster of considerable length, two or even more supporting elements may be employed.

Furthermore, the supporting element may, in certain embodiments of the invention, consist of 15 the connecting element 22 and either of the wing members 18 or 20 alone and still perform its two functions, namely, retaining the poster under tension and supporting it in display position.

Having thus described the invention, what I 20 claim to be new is:

1. A combined poster and support comprising a non-rigid poster, a channel shaped reinforcing member secured to the rear face of the poster at each end thereof, each of said reinforcing members being disposed entirely to the rear of the poster, said supporting means comprising a connecting element, wing members hingedly connected to opposite side edges of the connecting member, said wing members extending to the opposite ends of the connecting member and being movable to angular positions relative to the connecting member, said wing members each having a slot in its outer end for receiving one wall of their respective channel shaped reinforcing member when the poster is in its set up position, said slots also being spaced relative to the connecting member to provide portions upon the wing members for reception in the channel shaped reinforcing members when the device is in said set up position.

2. A poster of the type described comprising in combination, a non-self-supporting display panel, reinforcing elements fixed to each of two opposite side edges of said display panel, each of said reinforcing elements comprising a collapsible channel member, and means for supporting said display panel in display position, the supporting means comprising a collapsible member of channel cross sectional shape, and including 45 means for detachable engagement with the reinforcing elements of the display panel to retain the reinforcing elements in their set up position thereby to place the non self supporting display panel under tension and to retain the side walls 50 of the supporting means in fixed spaced relation to retain it in its set up display panel supporting position, and separate means for locking the supporting means in said set up position.

3. A poster of the type described comprising in combination, a non-self-supporting display panel, reinforcing elements fixed to each of two opposite side edges of said display panel, each of said reinforcing elements comprising an open collapsible channel member, and means for supporting said display panel in display position, the supporting means comprising an open collapsible member of channel cross sectional shape and including means for detachable engagement with the side walls of the reinforcing elements of the display panel to retain the reinforcing elements in their set up positions and to retain the open channel shaped supporting member in its set up display panel supporting position, and interlocking 70 tongues carried by the side walls of the channel

shaped supporting member for locking said member in its set up position.

4. A poster of the type described comprising in combination, a non-self-supporting display panel, reinforcing elements fixed to each of two opposite side edges of said display panel, each of said reinforcing elements comprising an open collapsible channel member, and means for supporting said display panel in display position, the supporting means comprising an open collapsible member of channel cross sectional shape and including means at each end for interengagement with the side

walls of its respective reinforcing element of the display panel to retain the reinforcing elements in their set up positions and to retain the open channel shaped supporting member in its set up position, said last mentioned means comprising cut out portions in each end of the side walls of the channel shaped supporting member for the reception of one wall of their respective display panel reinforcing elements.

RICHARD E. PAIGE.
